FOLDING CARTON

Robert J. Hickin, Seville, Ohio, assignor to The Ohio Boxboard Company, Rittman, Ohio, a corporation of Ohio

Application March 15, 1954, Serial No. 416,104

2 Claims. (Cl. 229—31)

This invention relates to folding paperboard cartons, and it is directed primarily to a modification of parts of folding cartons of known construction whereby the blanks therefor may more readily be set up by automatic or semi-automatic machinery and their cooperative parts secured in set-up condition.

To this end the invention comprises the provision of glue tabs partially cut from certain friction flaps normally provided for maintaining the carton parts in set-up condition, such tabs being capable, by virtue of the inherent resiliency of the paperboard material, of automatically departing, or offstanding, from the planes of the flaps from which they are cut to thus yieldingly engage, or wipe over, the surface of an adjacent part of the carton as it is being erected to set-up condition and thus to be automatically engaged with and adhered to adhesive applied between them and the said adjacent carton part, all as will be explained hereinafter more fully and finally claimed.

In the accompanying drawing illustrating the invention, in the several figures of which like parts are similarly designated,

Fig. 1 is a plan view of the inner side of a blank for a folding carton of known form provided with modifications in accordance with the invention,

Fig. 2 is a perspective view of a carton partially set up from the blank of Fig. 1,

Fig. 3 is a perspective view of the carton in fully set up condition, and

Fig. 4 is an enlarged, fragmentary sectional elevation taken in a plane passing medially through an end wall assembly of the set-up carton of Fig. 3.

As hereinbefore indicated, the blank shown in Fig. 1 is, aside from the modifications provided in accordance with the invention, of known form, and comprises a sheet of appropriate paperboard material provided with cuts and folding scores to produce a bottom wall element 1, similar side wall elements 2, and similar end wall elements comprising outer end wall members 3 and inner end wall members 4. The side wall elements 2 are foldable to erected set-up condition substantially normal to the bottom wall element 1 upon longitudinal folding scores 5, and the two-part end wall elements are similarly foldable upon transverse folding scores 6. Folding scores 7 arranged medially transversely of the end wall elements define their outer and inner members 3 and 4, respectively.

The outer end wall members 3 are joined to the ends of the side wall elements 2 by corner webs 8 defined therefrom by folding scores 9 and 10, respectively, and these corner webs are provided with diagonal folding scores 11. The inner end wall members 4 are provided on their lateral edges with friction flaps 12 and on their free or outer edges with friction flaps 13, these flaps being defined by folding scores 14 and 15, respectively.

In accordance with the invention, the folding scores 9, 11, 14 and 15 of the corner webs 8 and friction flaps 12

2

and 13 are preferably of spaced cut and score type in order to facilitate proper and ready relative folding of these parts when the carton is erected to set-up condition (Fig. 3) by automatic or semi-automatic machinery.

It will be apparent that in erecting this known type of folding carton blank to set-up condition the upward folding of the side wall elements 2 and end wall elements 3—4, substantially normal to the bottom wall 1, upon their respective folding scores 5 and 6 will cause the corner webs 8 to fold upon the folding scores 9 and 10 which connect them with the end and side wall elements, respectively, and upon their diagonal folding scores 11, so as to be flat-folded against the outer end wall members 3 (Fig. 2) and thus serve to anchor the side wall and outer end wall elements in erected condition when the inner end wall members are turned inwardly (Fig. 3) in substantial juxtaposition to the outer end wall members with their friction flaps 12 and 13 in frictional engagement with the side and bottom wall elements 2 and 1, respectively, with the thus folded corner webs between them.

It sometimes happens, when this type of carton is made of relatively heavy, or inherently springy, paperboard material such as would be required for the packaging of bulky or loosely packed articles, that the frictional engagement of the friction flaps 12 and 13 with the adjacent carton walls is not sufficient to maintain the desired set-up condition inasmuch as the inner end wall members 4 have a tendency to spring away from the outer end wall members 3 upon the folding scores 7. Also this may occur after the carton is set up and before it is filled with the commodity to be packaged. In any event, this type of failure will be a cause of annoyance and loss of packaging time, both of which must, if possible, be avoided in the interest of efficiency and economy.

In accordance with the invention each of the bottom wall engaging friction flaps 13 is provided with cuts defining a glue tab 16 yieldingly hinged upon the respective folding score 15 and capable of departing from the plane of its respective flap 13 when the latter is wiped to operative position in the setting up of the carton so that these tabs 16 will be certain to yieldingly engage the bottom wall 1. Thus, when spots of adhesive 17 (preferably quick-setting) (Figs. 1, 2, and 4) are applied to the bottom wall 1 adjacent to the folding scores 6 of the end wall elements and in position for engagement by the tabs 16 as they wipe over the bottom wall, this adhesive will serve to attach the glue tabs, and hence the inner end wall members 4, to the bottom wall, to thereby maintain the set-up condition of the carton.

It will be noted, particularly as shown in Fig. 4, that the slight beads produced by the longitudinal folding scores 5, when the side wall elements 2 are erected, have a tendency to support the bottom-engaging friction flaps 13 of the inner end wall members 4 out of contact with the bottom, thus, to an extent, defeating their intended frictional engagement with the bottom wall. The automatic displacement of the glue tabs 16 downwardly from the plane of the flaps 13, due to the inherent resiliency of the paperboard material at their folding scores 15, however, insures that these tabs will rather tenaciously yieldingly engage, or wipe against, the bottom wall, thus insuring their adhesion and attachment thereto in the presence of the interposed adhesive.

Conceivably, the adhesive might be applied to the glue tabs 16 rather than to the bottom wall, but in the erection of the carton to set-up condition by automatic or semi-automatic machinery it has been found expedient to deposit the spots of adhesive 17 upon the bottom wall 1, as shown, just prior to in-folding of the inner end wall members 4.

Various changes and modifications are considered to be within the principle of the invention and the scope of the following claims.

What I claim is:

1. In a carton comprising a plurality of walls relatively foldable to tray form, a bottom wall, an end wall element defined from said bottom wall by a first folding score and foldable upon such score substantially normal to said bottom wall, said end wall element including an outer member and an inner member defined from each other by a folding score in parallelism with said first folding score and arranged substantially intermediate the length of said element, and said inner and outer members being relatively foldable upon said intermediate score into substantially juxtaposed assembly, said inner member having at its free end a friction flap defined from it by a folding score parallel with said intermediate score and being foldable upon said parallel score into position substantially parallel with said bottom wall, a glue tab cut from said friction flap and connected with said inner member along said parallel score and capable of offstanding from the plane of said flap into wiping contact with the bottom wall independently of the body of said flap by bending action on said parallel score, and a spot of adhesive located upon said bottom wall adjacent to said first folding score and in position for contact by said tab, said tab thereby being capable of engaging said spot of adhesive when the end wall element is erected in juxtaposed assembly normal to said bottom wall to thereby effect stable erection of said end wall element by adhesion of 30 said tab to said spot of adhesive.

2. In a carton comprising a plurality of walls relatively foldable to tray form, a bottom wall, a pair of similar end wall elements each defined from said bottom wall by a first folding score, said end wall elements being 35

foldable upon such scores substantially normal to said bottom wall, each of said end wall elements including an outer member and an inner member defined from each other by a folding score in parallelism with the said 5 first folding score of the element and arranged substantially intermediate the length of said element, and said inner and outer members being relatively foldable upon said intermediate score into substantially juxtaposed assembly, the said inner member of each of said end wall elements having at its free end a friction flap defined from it by a folding score parallel with its said intermediate score and being foldable upon said parallel score into position substantially parallel with said bottom wall, a glue tab cut from the said friction flap of each of said 10 end wall elements and connected with the said inner member thereof along its said parallel score and capable of offstanding from the plane of said flap into wiping contact with the bottom wall independently of the body of said flap by bending action on said parallel score, and a spot of adhesive located upon said bottom wall adjacent to the said first folding score of each of said end wall elements and in position for contact by the tab of the adjacent end wall element, said tabs thereby being capable of engaging said spots of adhesive when the end wall elements are erected in juxtaposed assembly normal to said bottom wall to thereby effect stable erection of said end wall elements by adhesion of said tabs to said spots of adhesive.
